UNITED STATES PATENT OFFICE.

GEORGE A. HUNSINGER, OF PITTSBURGH, PENNSYLVANIA.

WRENCH.

1,112,800.

Specification of Letters Patent.

Patented Oct. 6, 1914.

Application filed February 2, 1914. Serial No. 815,854.

To all whom it may concern:

Be it known that I, GEORGE A. HUNSINGER, residing at Pittsburgh, in the county of Allegheny and State of Pennsylvania, a citizen of the United States, have invented or discovered certain new and useful Improvements in Wrenches, of which improvements the following is a specification.

My invention relates to pipe wrenches, and the object thereof is to provide a wrench, the lever arm of which is jointed and may be adjusted from a straight line shape to various angular forms adapted to render the wrench useful to tighten joints inaccessible to the ordinary straight and rigid handle wrench.

In the accompanying sheet of drawings, forming part of my specification and illustrating one embodiment of my invention, Figure 1 is a side view of the wrench, the lever arm being straight; Fig. 2 is a bottom plan view of Fig. 1; Figs. 3 and 4 are side views of the wrench illustrating two irregular positions of the lever arm; Figs. 5 and 6 are sectional views taken, respectively, on the lines V—V and VI—VI, Fig. 1; and Fig. 7 is a perspective view of the handle-locking member.

In the several figures like numerals are used to designate like parts.

Referring to the illustrative embodiment of my invention, an arm, consisting preferably of two spaced bars 1 and 1^a, is provided at one end with wrench jaws 2, 2^a, and at its opposite end a handle 3 is pivoted, the handle and arm forming the lever arm of the wrench. The jaws 2, 2^a may be of any desired form, those shown herein constituting the essential parts of an ordinary pipe wrench, the jaw 2 being adjustable, by means of a thumb screw 4, with relation to the jaw 2^a. The wrench jaws are pivoted to the arm 1, 1^a by means of a pin 5 rigidly secured to the jaw 2^a and extending through the bars, there being a portion of the pin protruding beyond the outer face of the bar 1. The handle 3 is preferably formed of two parts consisting of a bell crank lever 3^a and the gripping portion 3. A pin 6, rigidly secured to the lever portion 3^a, is rotatably mounted in the bars 1, 1^a and is provided with an angular head 7. The jaws 2, 2^a and the handle 3, 3^a being thus pivotally mounted at opposite ends of the arm 1, 1^a, means are provided to connect these members to

each other so that their pivotal movements may be simultaneously effected, and also that the force applied to the handle may be transmitted to the gripping jaws regardless of the angular position of the handle with relation to the arm 1, 1^a. The connecting means preferably consists of a link 8 pivoted to the outer end of one arm of the lever 3^a, and also pivoted to a crank arm 9 rigidly secured to the pin 5. By such an arrangement it will be seen that the force applied to the handle, when tightening or loosening a joint, will be effectively transmitted to the wrench jaws, and this regardless of the angle at which it may be necessary to adjust the handle 3 with respect to the arm 1, 1^a.

In using the wrench, the handle 3 may be locked in various angular positions with relation to the arm 1, 1^a, in which event the wrench jaws will also be locked in corresponding fixed positions; or the handle and jaws may have free pivotal movements. The handle 3, 3^a may be locked in alinement with the arm 1, 1^a, or at an angle thereto, by means of a bar 10 having an angular hole at one end and a round hole at the other. In Fig. 1 this bar is illustrated as simultaneously engaging the angular end 7 of the pin 6 and the protruding end of the pin 5, thus locking the handle 3 against movement with relation to the arm 1, 1^a, and hence (through bell-crank lever 3^a, link 8, crank arm 9 and pin 5) locking the jaws 2, 2^a with relation to said arm. When, as shown herein, a hexagonal head 7 is used, the handle 3 may be locked at angles of 45° on either side of the arm 1, 1^a; and, by using a head with a greater number of faces, more angular adjustments of the handle may be effected. Furthermore, when the handle 3 is detached, the bar 10 as illustrated in Fig. 4, may be used in place of the handle, and thus give a greater range of adjustment of handle with relation to the arm 1, 1^a.

A second means is provided for locking the handle 3 in alinement with the bar 1, 1^a. The handle is provided with a central stem 11 adapted to have screw-threaded engagement with the outer end of the lever 3^a, as seen in Fig. 6, and a locking member engages said stem and the arm bars 1, 1^a. The locking member is particularly illustrated in Fig. 7 and comprises a cap 12 adapted to fit upon the outer end of the lever 3^a, and tines 13 adapted to extend into open ended slots 110

formed in the ends of the arm bars 1 and 1^a. The cap 12 has a central threaded hole 14 of the same diameter and pitch as the threaded opening at the end of the lever 3^a.

5 When the handle 3 is attached to the lever 3^a, as indicated in Fig. 6, the locking member 12, 13 engaging the end of said lever and arms 1, 1^a, the wrench may be used as an ordinary straight-handle pipe wrench. In 10 case it is necessary to tighten a joint inaccessible to a straight handled wrench the handle 3 may be unscrewed, the locking member turned through an angle of 45° so that the tines will lie between the bars 1 15 and 1^a, and the handle again screwed to the lever. In making this change, it will be observed that, as the threaded end of the stem 11 is unscrewed from the end of the lever 3^a, the threaded hole 14 receives the threaded 20 stem 11. Thus the locking member remains attached to the handle, thereby facilitating the adjustment.

I claim as my invention:

1. In a pipe wrench, the combination of 25 an arm, a pair of gripping jaws pivotally mounted at one end thereof, means for adjusting said jaws to fixed relative positions, a handle pivotally mounted at the opposite end of the arm, and connecting means between said jaws and handle for effecting simultaneous pivotal movements thereof.

2. In a pipe wrench, the combination of an arm, a pair of gripping jaws pivotally

35 mounted at one end thereof, means for adjusting said jaws to fixed relative positions, a handle pivotally mounted at the opposite end of the arm, and a rigid link pivotally connected at its opposite ends to said gripping jaws and handle, the connections of 40 said link to the jaws and handle being eccentric with respect to their pivotal connections to said arm.

3. In a pipe wrench, the combination of an arm, a pair of gripping jaws provided with a pin pivotally mounted in one end of said arm, and having a crank arm rigidly secured thereto, means for adjusting said jaws to fixed relative positions, a handle pivotally mounted at the other end of said arm and provided also with a crank arm, and a link 50 pivoted at its opposite ends to the outer ends of each of said crank arms.

4. In a pipe wrench, the combination of an arm, a pair of gripping jaws pivotally mounted at one end thereof, means for adjusting said jaws to fixed relative positions, a handle pivotally mounted at the other end of said arm, and a single means for locking 55 said jaws and handle at a plurality of fixed positions with relation to said arm.

In testimony whereof I have hereunto set my hand.

GEORGE A. HUNSINGER.
